ATTORNEY.

UNITED STATES PATENT OFFICE.

FRANK M. STOLL, OF DENVER, COLORADO, ASSIGNOR TO THE ROCKY MOUNTAIN NOVELTY COMPANY, A CORPORATION OF COLORADO.

REFRIGERATOR.

Application filed August 7, 1923. Serial No. 656,212.

To all whom it may concern:

Be it known that I, FRANK M. STOLL, a citizen of the United States, residing at Denver, in the county of Denver and State of Colorado, have invented certain new and useful Improvements in Refrigerators, of which the following is a specification.

This invention relates to refrigerators and more particularly to refrigerating devices of the type in which the interior of a food receptacle is cooled by the evaporation of water at the surface of the porous outer wall of a surrounding jacket.

It is an object of the present invention to provide in a refrigerator of the above described character, an improved means for closing the entrance to the food receptacle, which effectively insulates the interior thereof from the surrounding atmosphere; a further object is to provide an improved method of connecting the outer porous wall of the refrigerator in spaced relation to the wall of the food receptacle, and still other distinctive features of the invention reside in the form of the supporting frame in which the refrigerator is suspended and in certain details of construction, all of which will be fully explained in the course of the following description with reference to the accompanying drawings.

In the drawings in the several views of which like parts are similarly designated,

Figure 1 represents a side elevation of the improved refrigerator;

Figure 2, a partially sectional end-view of the same;

Figure 3, a vertical section along the line 3—3, Figure 2;

Figure 4, a transverse section taken on the line 4—4, Figure 1;

Figure 5, a fragmentary section in the plane designated by the line 4—4, drawn to a much enlarged scale;

Figure 6, an enlarged section through one of the fasteners included in the construction of the outer wall of the refrigerator, taken on the line 6—6, Figures 1 and 2; and

Figure 7, an enlarged sectional elevation of one of the clamps by means of which the refrigerator may be fastened to the running board of a motor vehicle or other similar support.

Referring to the drawings, the reference

numeral 2 designates a receptacle preferably made of sheet metal in rectangular form, and provided with shelves 3 in suitable arrangement for the support of dishes, bottles, food stuffs and other articles to be preserved.

The receptacle which is open at its top, has around the edge of its opening, a trough-shaped rim 4 which is formed by bending the upper portions of its walls first upon themselves and then outwardly and upwardly as best shown in Figure 5 of the drawings.

The outer upright wall 4^a of the rim serves for the suspension of a bag 5 of canvas or other permeable fabric which provides the outer wall of a water jacket formed around the food receptacle.

The bag which is shaped in conformity with the receptacle is fastened to the rim by folding the upper portions of its sides inwardly about the outer wall thereof and securing said portions in place by means of a metal sheath 6 conforming in contour with the wall of the rim and fitting snugly upon the portions of the bag that are folded thereon. Bolts 7 passing through aligned holes of the wall, the bag and the sheath, and secured by nuts 8, fasten the parts together.

The open top of the food receptacle is normally closed by a flanged lid 9 which fits snugly upon the doubled upper portions of the walls thereof, and which is hinged by means of straps 10 fastened upon the horizontal member 4^b of the rim.

A pivoted ring 12 fastened to the lid at its edge opposite to that at which it is hinged, provides a convenient means to lift it to the open position, and a spring-catch 13 fastened to the rim co-operates with the ring to hold the lid in its closed position.

The top of the receptacle inclusive of its rim and its lid, is ordinarily enclosed by a flanged cover 14 which is fastened at one side of the outer wall of the rim by a flap 14^a inserted in the corresponding portion of the sheath and secured by the bolts which fasten the bag at the same side of the rim.

The cover 14 is provided with a pad 15 of felt or other insulating material, which rests upon the lid of the food receptacle, and its flange fits snugly upon the exterior portion of the sheath on the outer wall of the rim.

to which it is attached by means of snap fasteners 16 shown in detail in Figure 6.

A tube 17 fastened in an opening of the rim 4 and projecting through an aperture 5 in the canvas cover 14, provides a ready means for the supply of water to the jacket formed around the food receptacle, and a cock 15 fastened in an opening of the canvas bag at the bottom portion of the water space, is used to drain the water from the jacket for drinking, cleaning or other purposes.

The entire device constructed as hereinabove described, is suspended in a metal frame composed of two U-shaped members 18 fastened together by braces 19 and 20, and bent inwardly at their upper ends for their attachment to the rim of the food receptacle at opposite ends thereof.

20 The same bolts which fasten the upper portion of the bag to the wall of the rim and the enveloping sheath, may be employed to secure the receptacle to the frame.

The refrigerator if made in suitable proportions, is a most useful adjunct to the outfit of the automobile tourist and camper and in order that it may be carried on the vehicle without taking up space required for other purposes, I have provided a pair of 30 clamps by means of which it may be fastened to the running board.

The clamps shown in Figures 1, 2 and 7 of the drawings, each consist of a U-shaped bracket 22 adapted to embrace the foot board of an automobile and fitting against one of the cross braces 20 on the underside of the supporting frame of the refrigerator.

One of the arms of the bracket, which is longer than the other arm, has two holes 22a 40 one of which registers with a corresponding aperture of the cross brace. A bolt 23 inserted through the aligned openings, co-operates with a thumb-nut 24 to fasten the bracket to the supporting frame, and a screw 25 supported in a correspondingly threaded aperture at the end of the short arm of the bracket, has a swiveled head which by engagement with the underside of the running board or other support to 50 which the bracket is applied, clamps it in place.

It will be evident that the clamps are readily adjusted to a different position on the frame of the refrigerator by bringing 55 the other opening of their long arms in register with the corresponding apertures of the cross arms of the frame and that the clamps are easily removed in case it is desired to support the device without their use.

In the use of my improved refrigerator, the jacket around the food receptacle thereof, is filled with water through the tube 17, the mouth of which is normally closed by a 65 stopper 21. The water permeating the can-

vas wall of the jacket evaporates at the surface thereof and by said evaporation cools the water within the jacket.

The cooled body of water surrounding the metal walls of the food receptacle, maintains 70 a low temperature within the receptacle for the preservation of articles of food placed upon its shelves, and the tight-fitting lid of the food receptacle in conjunction with the padded and flanged canvas covering, insulates the contents of the receptacle from the influence of the atmosphere at the top thereof.

It will be apparent that the means for fastening the canvas bag in spaced relation 80 to the walls of the receptacle, provides a simple, secure and leak-proof joint; that the sheath included in said means furthermore provides a protective envelope for the upper portion of the canvas, which prevents 85 wear and injury of the fabric; that the spring catch functions to force the metal lid of the receptacle to its closed position, and that the entire structure inclusive of the supporting frame, is designed to combine 90 simplicity and economy of construction with efficiency and practicability in use.

Having thus described my invention, what I claim and desire to secure by Letters Patent is:

1. A refrigerator of the character described, comprising a food-receptacle having a trough-shaped rim projecting laterally from its walls, a porous bag fastened at the outer portion of the rim in spaced relation to the walls of the receptacle, and a lid fitted upon the inner portion of the rim.

2. A refrigerator of the character described, comprising a food-receptacle having a trough-shaped rim projecting laterally from its walls, a porous bag spaced from the walls of the receptacle and folded upon the outer wall of the rim, and means for fastening the bag to said wall.

3. A refrigerator of the character described, comprising a food-receptacle having a trough-shaped rim projecting laterally from its walls, a porous bag spaced from the walls of the receptacle and folded upon the outer wall of the rim, a sheath fitted over the portion of the bag engaging with the rim, and means for fastening the sheath and the part of the bag within the same, to the rim.

4. A refrigerator of the character described, comprising a food receptacle having below its upper edge, an outwardly projecting rim, a porous bag fastened on the rim in spaced relation to the walls of the receptacle, and a flanged lid fitting over said upper edge of the receptacle.

5. A refrigerator of the character described, comprising a food receptacle having below its upper edge, a laterally projecting rim, a fabric bag fastened on the rim in

spaced relation to the walls of the receptacle, a lid closing the top of the receptacle, and a fabric cover over the lid, movably fastened to the rim and co-operating with the bag to completely enclose the receptacle.

6. A refrigerator of the character described, comprising a food receptacle having below its upper edge, a laterally projecting rim, a fabric bag fastened on the rim in spaced relation to the walls of the receptacle, a lid closing the top of the receptacle, and a fabric cover movably fastened to the rim and having a pad that covers the lid.

7. A refrigerator of the character described, comprising a food receptacle having a trough-shaped rim projecting laterally from its walls, a fabric bag fastened on the outer wall of the rim in spaced relation to the walls of the receptacle, a flanged lid fitted upon the inside wall of the rim, and a flanged fabric cover fitted over the outer wall of the rim and hinged at one side thereof.

8. A refrigerator of the character de-

scribed, comprising a food receptacle having 25 a trough-shaped rim projecting laterally from its walls, a fabric bag spaced from the walls of the receptacle and folded over the outer wall of the rim, a sheath fitted over the portion of the bag engaging with 30 the rim, a lid closing the top of the receptacle on the inside of the rim, a flanged fabric cover fitted over the outer wall of the rim and having a flap fastened inside the sheath at one side of the rim, and means for 35 fastening the sheath and the parts of the bag and the cover within the same, to the rim.

9. A refrigerator of the character described comprising a food receptacle having 40 an outwardly projecting rim, a lid for the receptacle, a bag fastened to the rim in spaced relation to the walls of the receptacle, and a support for the receptacle connecting with the rim.

In testimony whereof I have affixed my signature.

FRANK M. STOLL.
